UNITED STATES PATENT OFFICE

JOHN R. LUNDBERG, OF MAPLEWOOD, NEW JERSEY

DESIGN FOR AN EMBROIDERED SCARF

Application filed August 18, 1931. Serial No. 40,880. Term of patent 3½ years.

To all whom it may concern:

Be it known that I, JOHN R. LUNDBERG, a citizen of the United States of America, residing at Maplewood, in the county of Essex and State of New Jersey, have invented a new, original, and ornamental Design for Embroidered Scarfs, of which the following is a specification, reference being had to the accompanying drawing, forming part thereof.

The figure is a plan view of an embroidered scarf showing my design.

I claim:

The ornamental design for an embroidered scarf as shown.

JOHN R. LUNDBERG.
